ABSTRACT OF THE DISCLOSURE

An electromagnet having an elongated coil provided with longitudinally extending parallel sides and curved ends of saddle-shaped configuration, with the coil composed of a plurality of layers, a layer-receiving means defining a groove which receives the winding layers and which has elongated parallel sides and saddle-shaped ends conforming to the configuration of the winding layers.

Our invention relates to electromagnets, and especially to electromagnetic coils.

Our invention relates in particular to electromagnet coils capable of providing magnetic fields which are not circumferentially symmetrical, such as, for example, longitudinally elongated transverse fields or quadrupole fields. Fields of this type are required for different technical and scientific purposes. Coils of this type are particularly useful in those cases where charged particles, such as, for example, ions, electrons and other elementary particles, are to be exposed to a transverse magnetic field, which is to say a magnetic field which extends perpendicularly with respect to the direction of movement of the particles. Such coils are therefore particularly required to act as direction-changing magnets for magnetohydrodynamic generators and particle accelerators.

In order to achieve longitudinally elongated transverse fields, it is known to use separate coil sections which form an intermediate space passing through the coil. Such coils have a pair of cylindrical windings of oval cross section. The particles whose direction of movement is to be changed can enter into the intermediate space between the pair of coils into the magnetic field which extends primarily longitudinally of the cylinder, and the particles also leave the coil through this intermediate space. Such coils have the disadvantage of creating undesirable stray losses resulting from the intermediate space between the windings, and these stray losses result in distortion of the field precisely at that part thereof through which the particles whose direction is to be changed pass. Therefore, a homogeneous field is situated only in a relatively small region within the coil. Moreover, the field which is available for changing the direction of the particles is weakened by the field losses which occur in the intermediate space.

It is possible to prevent, in part, the field losses and distortions resulting from the use of separated coil sections by refraining from using, to achieve the transverse magnetic fields, an intermediate space between the windings which passes completely through the coil. It is possible to use instead a coil having a pair of elongated windings provided with longitudinally extending sides which engage each other and with ends which are curved to a saddle-shaped configuration in such a way that the interior of the coil is accessible at the ends of the windings for the particles whose direction is to be changed. Inasmuch as the ends of the windings are curved with a coil of this type, the individual windings of the coil are no longer situated in a single plane.

With a coil whose windings have this type of saddle-

2

shaped curvature at their ends there is, however, the difficulty of forming the coil in such a way that a high winding density, and therefore a small wire consumption is achieved, and there is in addition the problem of making it possible to manufacture such coils with winding machines. If the coil windings initially have an oval, flat form and then are curved upwardly, then during the upward bending the individual wires of the coil shift one with respect to the other. As a result only a relatively low wire density, or filling factor, is achieved. When the winding is carried out by machine on a winding body, the windings can only be mounted in a relatively loose form, since otherwise the bending of the wound coil body is not possible.

Similar difficulties are encountered with magnet coils having more than two windings for achieving magnetic fields which are not circumferentially symmetrical, such as, for example, quadrupole fields.

It is a primary object of our invention to provide an electromagnet coil having elongated windings which have longitudinally extending sides which are parallel to each other and which have ends curved to a saddle-shaped configuration, while avoiding all of the above problems.

A further object of our invention is to provide for winding layers of the coil a layer-receiving means which enables the coil to be continuously wound with wire which is maintained under tension during the winding of the layers and with the winding being carried out in such a way that lateral slipping of the wire during winding thereof is prevented.

It is therefore an object of our invention to provide a magnet coil which is made up of a particularly dense, strong assemblage of windings having a high filling factor.

Furthermore, it is an object of the invention to provide for the coil its final configuration during its manufacture, so that bending of the coil after manufacture thereof is unnecessary and thus shifting of the wires one with respect to the other is avoided.

It is a particular object of our invention to provide an electromagnet coil composed of superconductive wire. It is especially when superconductive wire is used that a dense strong construction of the coil is required so that with the smallest possible length of wire the greatest possible magnetic field can be achieved.

Furthermore, the objects of our invention include the provision of a coil which can be manufactured with a conventional winding machine.

Our invention also includes the provision of a layer-receiving means which is capable of absorbing the forces which act on the coil windings and which result from the magnetic field encountered during operation of the coil. Particularly with superconductive coils these forces are especially great because of the strong magnetic field.

The electromagnet of our invention has an elongated coil provided with longitudinally extending parallel sides and curved ends of saddle-shaped configuration, with the coil composed of a plurality of winding layers located one adjacent the other with the windings of any one layer all having the same length and with the portions of the windings which extend along the sides of any one layer all being located in a common plane. The coil of our invention further includes a layer-receiving means defining a groove which receives the winding layers and which has elongated parallel sides and saddle-shaped ends conforming to the configuration of the winding layers.

Our invention is illustrated by way of example in the accompanying drawings which form part of this application and in which:

FIG. 1 is a schematic perspective illustration of one winding layer of a coil of our invention;

FIG. 2 is a perspective illustration of a pair of layer-

receiving means of our invention joined together to form an electromagnet coil;

FIG. 3 is a perspective illustration of a special embodiment of a layer-receiving means of our invention;

FIG. 4 is a fragmentary perspective illustration of the layer-receiving means of FIG. 3, the section of FIG. 4 being taken in a plane which extends perpendicularly with respect to the longitudinal sides of the coil;

FIG. 5 is a fragmentary perspective illustration of another embodiment of a layer-receiving means of our invention, the section of FIG. 5 also being taken in a plane which extends perpendicularly across the longitudinally extending sides of the coil;

FIG. 6 is a fragmentary perspective illustration of the winding layers, the section of FIG. 6 also being taken in a plane which extends transversely across the longitudinal sides of the coil and FIG. 6 schematically showing the electrical connections for the coil;

FIG. 7 is a perspective illustration of a further embodiment of a coil according to our invention;

FIG. 8 is a fragmentary perspective illustration of yet another embodiment of a layer-receiving means of our invention, the section of FIG. 8 being taken in a plane which extends perpendicularly across the longitudinal sides of the coil; and

FIG. 9 is a fragmentary perspective illustration of yet another embodiment of a layer-receiving means of our invention, the section of FIG. 9 also being taken in a plane which extends perpendicularly across the sides of the coil.

The configuration of a winding layer of the electromagnet coil of our invention can best be understood by visualizing an endless band of uniform width having opposed edges of uniform length, this band initially having the configuration of a cylinder and then being deformed in such a way that a pair of opposed portions of the band are turned into a common plane with the edges of the band portions which are in the common plane extending parallel to each other, so that the inner surfaces of the two turned band portions are situated on the same side of the plane. An endless band of the above construction which has been treated in the above manner is illustrated in FIG. 1 which shows the pair of turned elongated band portions 1 and 2 which form the longitudinally extending sides of the coil, these band portions 1 and 2 extending parallel to each other in a common plane. As a result of this deformation of the initially cylindrical endless band, the end portions 3 and 4 of the band, which form the ends of the coil, have the saddle-shaped curvature shown in FIG. 1. This band which is of uniform width is a model for a winding layer of the coil, this layer being composed of wire windings situated one next to the other. Inasmuch as the band in its initial cylindrical form has edges of uniform length, it follows that all lines drawn on the band parallel to the edges thereof are necessarily of the same length. Therefore, the individual wire windings which conform to the configuration of the band edges and thus correspond to such lines necessarily have within the layer of our invention equal lengths. By bending the ends to different extents, illustrated by an outward bulging of the upwardly curved band ends, it is possible to vary the configuration of the coil.

By combining additional layers of a configuration similar to that of FIG. 1 with the layer illustrated therein, all of the winding layers of the coil will result. All of the winding layers are oriented in the same way so that one layer extends along and is located adjacent the other. The configuration of the coil is described in greater detail in connection with the description of the layer-receiving means below. While the lengths of the individual windings of any one layer are equal, the winding lengths increase from one layer to the next.

In order to provide elongated transverse fields, the electromagnet coil of our invention is made up of two or more coil sections each having a pair of elongated

sides, and these coil sections are arranged with their longitudinally extending sides engaging each other. FIG. 2 shows a pair of layer-receiving means 21 and 22 which are connected together to form a coil according to our invention, the winding layers being omitted from FIG. 2 so as to show more clearly the details of the pair of interconnected layer-receiving means 21 and 22. Each of these layer-receiving means has a pair of longitudinally extending sides which are parallel to each other and a pair of saddle-shaped opposed ends curved as illustrated in FIG. 2. The interior space of the coil of our invention is, because of the curvature of the ends, accessible from the exterior in a direction which extends perpendicularly with respect to the magnetic field produced by the structure. Each of the layer-receiving means 21 and 22 defines a groove which serves to receive the winding layers. The groove of the layer-receiving means 22 is described below, and of course, the layer-receiving means 21 is formed with an identical groove which is directed toward the groove of the layer-receiving means 22. Thus, the layer-receiving means 22 has an inner base surface 23 which defines the base of the layer-receiving groove and which has a configuration conforming to that of the band of FIG. 1. Thus, the configuration of the base of the groove matches the configuration of the first winding layer. The layer-receiving means 22 has a pair of side walls 24 and 25 which extend perpendicularly with respect to the base surface 23 along the entire length thereof, and it is these side walls 24 and 25 which have the inner side surfaces of the layer receiving means 22 which define the opposed side surfaces of the layer-receiving groove. As was mentioned above, the groove of the layer-receiving means 21 is of the same configuration.

During manufacture of the coil, the individual winding layers are wound within the groove in such a way that the individual windings in any one layer all have the same length. At the junctions 26 between the curved end portions and elongated side portions of the layer-receiving means 22, the side walls 24 and 25 thereof bulge outwardly, thus providing a widening of the coil body. As a result the individual winding layers of the coil each have their individual windings of equal length situated along the sides of the coil at a density which is different from their density at the ends of the coil. In order to provide a mechanically strong coil under these conditions, it is preferred to include with the layer-receiving means 21 and 22 suitable intermediate shims or the like of insulating material which are situated at the ends of the coil between the individual layers. As a result there is a small loss of winding density. This disadvantage is, however, compensated to a very large extent by the relatively simple geometric configuration of the layer-receiving means. Each layer-receiving means can be manufactured in a relatively easy way. The introduction of the windings can take place in a simple way by using a conventional winding machine.

An outward bulging of the side walls at the junction between the curved end portions and the longitudinal sides is prevented with the embodiment of our invention which is illustrated in FIGS. 3 and 4. The layer-receiving means of this embodiment includes a pair of side walls 31 and 32 which have inner surfaces defining the opposed inner side surfaces of the groove. These side walls are interconnected by a transverse wall 33 which has an inner surface defining the base surface of the groove. With this embodiment the outer side wall 31 and the inner side wall 32 extend perpendicularly with respect to the transverse wall 33 only along the elongated sides of the layer-receiving means. At the junctions between the curved ends of the layer-receiving means and the longitudinally extending sides thereof, the angle between the outer side wall 31 and the transverse wall 33 becomes smaller while the angle between the inner side wall 32 and the transverse wall 33 becomes greater. The saddle-shaped ends of the layer-receiving means respectively have crests 34, and at this crest

34 the outer side wall 31 extends from the transverse wall 33 at an angle of from approximately 30° to 35° , while the inner side wall 32 extends from the transverse wall 33 at the crest of each end at an angle of from approximately 150° to 145° . Thus, the total of both of these angles is 180° . At the crest of each saddle-shaped end, the side walls of the layer receiving means extend substantially parallel to that part of the wall 33 which extends along each side of the layer-receiving means.

In FIG. 3 the configuration of the inner space defined by the walls 31-33 is partially indicated in dotted lines. At the ends of the layer-receiving means, the side walls 31 and 32 have a width which is more than twice their width along the sides of the layer-receiving means. The configuration of the base of the groove corresponds to the configuration of the first winding layer of the coil of our invention.

The shape of the coil and thus the configuration of the groove of the layer-receiving means can be best illustrated by a paper model. Thus, a plurality of endless paper strips all of the same width but each of a length somewhat greater than the next are joined together in a coextensive identically oriented manner with the strip of FIG. 1, this latter strip forming what corresponds to the first winding layer. Thus, the additional strips will correspond to the additional layers of the coil. The gluing of the several paper strips one to the other is carried out in such a way that the edges of the assembled strips will define surfaces which illustrate the configuration of the surface of the groove of the layer-receiving means, and along the sides the model of the coil will have surfaces extending perpendicularly with respect to the elongated side portions of the first band shown in FIG. 1. At the ends of the model the surfaces defined by the edges of the joined strips will form angles on the one hand of from approximately 30° to 35° and on the other hand, of from approximately 150° to 145° with the end portions 3 and 4 shown in FIG. 1, these end portions of course corresponding to the base surface of the groove. Inasmuch as these individual paper strips represent the different winding layers situated one on the other and conform precisely to the configuration of the groove of the layer-receiving means, this model provides an accurate representation of the structure of the coil and its groove.

As is apparent from the above-described construction of a model which represents the coil of our invention, it is possible with the embodiment of FIGS. 3 and 4 to arrange the individual winding layers directly one upon the other, so that intermediate layers or shims of insulating material or the like are not required.

With an electromagnet coil having a pair of layer-receiving means as shown in FIG. 3 joined together with their longitudinal sides engaging each other and with corresponding windings situated in the grooves of the layer-receiving means, the maximum field intensity is situated at the central plane of the coil, this central plane being defined by the free edges of the side walls 31 and 32 at the longitudinal sides thereof. Of course, it is the free edges of one set of side walls, at the sides of the layer-receiving means which engage, respectively, the free edges of the other pair of side walls of the other layer-receiving means along the sides thereof. Deviations above and below this central plane will provide field changes of approximately one percent. The field changes resulting from deviations from the longitudinal axis of the coil within the central plane thereof are on the order of 2%. Because of these small deviations, it is possible to achieve with the coil of our invention magnetic fields having a high degree of homogeneity.

With magnetic fields which have their maximum intensity not in the central plane between the pair of coil sections, but above or below this central plane, it is possible to provide a coil according to our invention having windings which in cross section are provided along the sides of the coil not with the configuration of a rectangle

but rather with the configuration of a rhombus. Thus, the groove of a layer-receiving means which serves to receive the winding layers of such a coil has a corresponding configuration.

FIG. 5 shows such a layer-receiving means, and it will be seen that the groove of the layer-receiving means of FIG. 5 has indeed the configuration of a rhombus in cross section. Thus, along the longitudinally extending sides of the layer-receiving means, the outer wall 51 extends from the transverse wall 52 at an angle of approximately 120° and the inner wall 53 extends from the transverse wall at an angle of approximately 60° . At the crest 54 of each curved end portion, the outer wall 51 extends from the transverse wall 52 at an angle which ranges from approximately 40° to 45° , and the inner wall 53 extends at the crest of each curved end portion from the transverse wall 52 at an angle ranging approximately from 140° to 135° . Thus, these angles also total 180° . The precise configuration of the groove can be demonstrated by a model made up of paper strips in the same way as described above in connection with FIG. 3. The strips are glued one to the other in such a way that the edges thereof conform to the surfaces which define the sides of the groove, while the base of the groove conforms to the configuration of the first strip. With such a model it will be found that the above angles are indeed provided. At the crests of the curved ends, the inner and outer side walls of the layer-receiving means extend approximately parallel to the transverse wall 52 at its portions which extend along the sides of the layer-receiving means.

With a coil which is composed of a pair of layer-receiving means as shown in FIG. 5 connected one to the other with the free edges of the side walls of one layer-receiving means engaging the free edges of the side walls of the other layer-receiving means, along the sides of the coils, it has been found that with the winding layers situated in the layer-receiving means and with the coil in operation, the magnetic field will initially increase in intensity proceeding from the central plane, to an extent of approximately 25%, and then the intensity will decrease.

The angles between the base surface of the groove and the side surfaces thereof at the ends of the layer-receiving means of our invention can have different values, provided only that the windings received within the layer-receiving means all have the same length in any one layer, which is to say the configuration of the winding layer and the form of the groove correspond to the models referred to above and made from the joining together of the endless paper strips which define at their edges the surfaces corresponding to those of the groove. Of course, each endless paper strip has opposed edges of the same length, as pointed out above. The particular angles referred to above, namely the angles of from 30° to 35° , on the one hand, and 150° to 145° , on the other hand, as well as the angle of from 40° to 45° , one the one hand, and 140° to 135° , one the other hand, have, however, proved to be very satisfactory since at these angles the windings of each layer can have a relatively short length. Thus, this feature is of significance with respect to saving of wire of the coil.

FIG. 6 fragmentarily illustrates the winding layers of a coil of our invention without the layer-receiving means. The coil is composed of several winding layers 61 which are formed in such a way that the individual winding 62 within any one layer all have the same length. At one of the longitudinal sides of the coil, the wire ends 63 of the coil extend outwardly and are connected with a source of current 64. The switch 65 serves to connect the source of current 64 into the circuit or to open the circuit. When the coil is composed of superconductive wire, there is an additional superconductive switch 66 for closing the superconducting circuit during superconductive operation.

It is also possible in accordance with our invention to provide a layer-receiving means which does not receive the entire winding layers, so that this layer-receiving means

does not form a single endless groove. In many cases it is sufficient if the layer-receiving means only partially receives the winding layers, particularly at the curved end portions which are difficult to shape. With a construction of this type, the portions of the sides of the winding layers which extend between the sections of the layer-receiving means can be rigidly held together by pouring a mass about these portions of the winding layers in a suitable mold in which the mass solidifies so that thereafter the portions of the winding layers which extend beyond and between the sections of the layer-receiving means will remain rigid.

A coil of our invention which includes such a layer-receiving means is illustrated in FIG. 7 where the layer-receiving means is composed of a pair of sections 71 and 72 which are separate and spaced from each other and which respectively receive the saddle-shaped ends 74 and 73 of the winding layers. The longitudinal side portion 75 of the winding layers extend freely beyond the sections 71 and 72 of the layer-receiving means. The ends 76 of the coil are directed outwardly to the side, as schematically indicated in FIG. 7.

When using superconductive wire for the windings of the coil, it is of advantage to give the layer-receiving means an exceedingly strong construction so that it will be able to absorb the mechanical forces encountered as a result of the exceedingly intense magnetic fields of superconductive coils. The layer-receiving means need not have in this case the rail-like configuration, as has been chosen for illustration in FIGS. 2-5 for the sake of greater clarity. In this case it is preferred to make the layer-receiving means in the form of a massive metal member formed with a groove only for the purpose of receiving the winding layers and having in the longitudinal direction of the coil an elongated space provided for the particles which are introduced into the magnetic field. Thus, other portions of such a massive body remain as support material to provide mechanical strengthening of the layer-receiving means. It is of particular advantage to use reinforcing ribs with such a construction. Where the coil is composed of a plurality of coil sections, the plurality of layer-receiving means can be connected to each other by screws.

FIGS. 8 and 9 show a pair of layer-receiving means having these features. The layer-receiving means 81 of FIG. 8 is provided between its portions which are formed with the groove 82, which receives the winding layers, with a bridging wall 83 which considerably strengthens the structure and which defines part of an elongated passage or canal 84 over which the bridging wall 83 extends and in which the magnetic field is situated. The outer wall of the layer-receiving means 81, which defines the outer surface of the groove 82, is fixed with lugs 85 which serve, in connection with suitable bolts, nuts and the like to fix the layer receiving means of FIG. 8 with another layer-receiving means providing an arrangement such as that shown in FIG. 2, for example.

With the layer-receiving means 91 of FIG. 9, there is in addition to the bridging wall 92 between the sides of the groove 93 a reinforcing rib 94 which extends integrally from the bridging wall 92 as well as from the transverse wall which defines the base of the groove 93. The passage 95 is provided for the magnetic field.

For the manufacture of the layer-receiving means of the invention it is desirable to use strong metal which can be readily worked. For example, the layer-receiving means in its final form can be derived from an aluminum casting. Also, it is possible to manufacture the layer-receiving means from copper into which is milled the groove for receiving the winding layers. The use of a material of good heat conductivity, such as aluminum or copper, for the layer-receiving means will facilitate cooling of the coil, particularly when superconductive coils are used. In order to improve the cooling the groove-defining side walls may be formed with additional

openings which permit the entrance of a cooling medium to the coil windings. Because of the good electrical conductivity of materials such as copper and aluminum, the layer-receiving means formed from these metals can simultaneously serve with superconductive coils as short-circuiting rings to prevent damaging of the coil during the transition between the superconducting and the normal conducting states.

As superconductive wire for the coil it is possible to use, for example, niobium-zirconium wire. When using cables made up of several niobium-zirconium wire filaments housed within a plastic sleeve or envelope, the winding process is considerably simplified. It is also possible to use, for example, wires, bands or cables made of niobium-tin (Nb₃Sn), or layers of niobium-tin can be used. In the event that such niobium-tin superconductors are to be shaped after the manufacture of the coil at temperatures of from approximately 950° to 1000° C., the layer-receiving means cannot be made of aluminum, inasmuch as this material has a melting point which is too low, and in this case copper will be used for the layer-receiving means.

During operation in the superconducting state, the entire coil is situated in a cryostat in order to achieve the required low temperatures.

The magnet coils of our invention have many uses. The magnet coil formed from two or more coil sections, according to our invention, which achieve a magnetic field whose maximum intensity is situated in the central plane of the coil, are particularly suitable for use with magnetohydrodynamic generators. Where the coil is composed of two or more coil sections having their maximum field intensity beyond the central plane of the coil, the coil is suitable for use as a guiding magnet for the particle accelerator since the particles whose direction is to be changed often do not pass with such devices through the central plane of the coil.

As was mentioned above, the winding layers of the coil of our invention can be wound on conventional winding machines in which the wire is maintained under tension. Because all of the windings which in any one layer are of the same length are wound in a position where the pressure derived from a wire during its winding is always directed perpendicularly against the support beneath the wire, a lateral shifting of the wire during the winding of the layers is prevented.

The configuration of the cross section of the groove in the layer-receiving means of the coil of our invention will depend upon the form of the magnetic field which is to be achieved with the coil. Thus, in those cases where the magnetic field is to have its greatest intensity in the central plane between the pair of coil sections, the side surfaces of the groove will have along the sides of the coil an angle of 90° with respect to the base surface thereof. This angle can be maintained throughout the entire length of the groove or it may vary along the length of the groove, as pointed out above. The depth of the groove, which is to say the width of the side surfaces thereof, is selected in such a way that all of the winding layers will be received therein.

We claim:

1. In an electromagnet, a coil comprising a plurality of winding layers located one adjacent the other with a plurality of windings forming each layer, all of the windings of any one layer being of the same length and each layer having a pair of elongated parallel sides and a pair of opposed ends respectively curved from said sides and having a saddle-shaped configuration, the winding portions which form the sides of any one layer all being located in a common plane, and a layer-receiving means defining a groove receiving said layers at least in part, said groove having saddle-shaped ends respectively receiving said ends of said layers and elongated sides respectively receiving said sides of said layers, and said layer-receiving means having an inner base surface of

uniform width defining the base of said groove and a pair of opposed inner surfaces defining the sides of said groove and terminating in free edges which are located in a common plane along the sides of said groove.

2. A coil as recited in claim 1 and wherein said inner side surfaces extend perpendicularly with respect to said base surface.

3. A coil as recited in claim 1 and wherein said layer-receiving means has a pair of opposed groove walls respectively provided with said inner side surfaces of said groove, one of said groove walls being an outer wall and the other of said groove walls being an inner wall and said walls extending perpendicularly with respect to said base surface along the sides of said groove, said groove walls respectively having crests at each of the saddle-shaped ends of said groove and said outer wall extending at each crest at an angle of less than 90° from the base surface of said groove while said inner wall extends at each crest from the base surface of the groove at an angle which when added to said angle of less than 90° totals 180°.

4. A coil as recited in claim 3 and wherein said angle of less than 90° ranges approximately from 30° to 35° while said angle at which said inner wall extends from said base surface at each crest ranges approximately from 150° to 145°.

5. A coil as recited in claim 1 and wherein said sides of said groove have in cross section the configuration of a rhombus, said layer-receiving means having outer and inner side walls respectively provided with said inner side surfaces of said groove and said side walls respectively having crests at each saddle-shaped end of said groove, said outer wall extending from said base surface of said groove at each crest at an angle of less than 90° and said inner wall extending from said base surface of said groove at each crest at an angle which when added to said angle of less than 90° total 180°.

6. A coil as recited in claim 5 and wherein said outer wall extends at the sides of said groove from said base surface thereof at an angle of approximately 120° while said inner wall extends from said base surface of said groove along the sides thereof at an angle of approximately 60°, and said angle of less than 90° ranging approximately from 40 to 45° while said angle which, when

added to said angle of less than 90° totals 180°, range approximately from 140° to 135°.

7. A coil as recited in claim 1 and wherein said layer-receiving means includes a pair of spaced bodies respectively receiving said ends of said layers and said sides of said layers having portions which extend between said bodies.

8. A coil as recited in claim 1 and wherein said layer-receiving means is in the form of an aluminum casting.

9. A coil as recited in claim 1 and wherein said layer-receiving means is in the form of a copper body in which said groove is formed.

10. In an electromagnet, a coil comprising a plurality of winding layers located one adjacent the other with a plurality of windings forming each layer, all of the windings of any one layer being of the same length and each layer having a pair of elongated parallel sides and a pair of opposed ends respectively curved from said side and having a saddle-shaped configuration, the winding portions which form the sides of any one layer all being located in a common plane, and a layer-receiving means defining a groove which receives said layers, said layer-receiving means having an inner base surface defining the base of said groove and a pair of opposed inner side surfaces defining the sides of said groove, and said layer-receiving means having an outer wall provided with one of said inner surfaces, an inner wall provided with the other of said inner side surfaces, and a bridging wall extending across the space between and interconnecting those portions of said inner wall which extend along the sides of said groove.

11. A coil as recited in claim 10 and wherein said layer-receiving means has at least one exterior rib projecting from said bridging wall.
